PHONOGRAPH CABINET

Carl W. Sundberg, Bloomfield Hills, Mich., and Theodore A. Dobson, Chicago, Ill., assignors to The Seeburg Corporation, Chicago, Ill.

Filed Nov. 2, 1962, Ser. No. 72,350

Term of patent 14 years

(Cl. D56—4)

FIGURE 2

FIGURE 3

FIGURE 1 is a perspective view of a phonograph cabinet, showing our new design;

FIGURE 2 is a top plan view on a reduced scale; and

FIGURE 3 is a side elevational view thereof on a reduced scale.

The side not shown is substantially the same as the side shown, and the rear is plain and unornamented.

The dominant features of our design reside in the portions shown in full lines.

We claim:

The ornamental design for a phonograph cabinet, substantially as shown and described.
